UNITED STATES PATENT OFFICE

2,573,995

STORAGE TANK CONSTRUCTION

Joseph T. Sparling, Los Angeles, Calif.

Application March 3, 1947, Serial No. 731,999

1 Claim. (Cl. 220—1)

1

This invention relates to new and useful improvements in tank structures and method of facilitating erection and dismantling thereof. The principal object of the present invention is to provide a tank structure which is initially composed of sections and the sections are subsequently set up, bolted and welded together thus saving considerable time and labor. Another object is the production of a tank in which panels or sections constituting a vertical wall or shell are secured together by uninterrupted welded joints extending vertically from bottom to top. Said panels or sections may be of even thickness from bottom to top or may be in the form of a series of members successively diminishing in thickness upwardly, or may gradually taper in thickness from bottom to top. Other objects and advantages of the invention will be apparent from the following description.

In the drawings forming part of this specification, Fig. 1 is a plan of a portion of my improved tank with the roof removed and showing pairs of erecting and dismantling runners resembling channel members in place for bolting the vertical abutting edges of the side wall panels or sections juxtaposed in position in readiness to be welded; Fig. 2 is an inside elevational view of a portion of the tank illustrated in Fig. 1, showing only one pair of the erecting and dismantling runners; Fig. 3 is a side elevational view of a detail at an enlarged scale showing portions of the shell sections or panels assembled and held with their abutting vertical edges juxtaposed in readiness for welding by a pair of erecting and dismantling channel runners; Fig. 4 is a plan looking down upon the detail portion of the tank shown in Fig. 3; Fig. 5 is a vertical section taken approximately on the line 5—5 of Fig. 3; Figs. 6 and 7 are vertical sections like in Fig. 5 showing alternative types of tank sections or panels to which the channel runners are shown applied to facilitate erecting and dismantling; Fig. 8 is a plan of my improved tank, a portion of the roof paneling being removed to expose the radiating roof rafters which are employed in the tank structure; Fig. 9 is an elevation in section looking at a portion of the structure shown in Fig. 8; Fig. 10 is a schematic elevational view of a detail portion of the roof structure illustrating the manner in which the setting up channels are afterwards used as roof rafters; Fig. 11 is a sectional detail illustrating a construction of the setting up channel runners in which longitudinal sections thereof secured by their ends are employed; Fig. 12 is a section of a detail illustrating another method of construction which

2

may be employed at times in the setting up operation; Fig. 13 is a typical cross section of a detail showing a pair of setting up vertical channel runners applied to abutting portions of a pair of side wall panels or wall sections of the tank and a welding torch applied in use by the channel runners the vertical seams between said panels; Fig. 14 is a front elevation of a detail showing the application of a staging or bracket structure to the erecting channel runners for manual support; Fig. 15 is a side elevation of the structure shown in Fig. 14; Fig. 16 is an inside elevation of a detail of the tank structure showing the use and construction employed for securing the vertical abutting portions of the tank panels or sections together by an outside vertical field weld; Fig. 17 is a section taken on the line 17—17 of Fig. 16; Fig. 18 is a cross section of a detail similar to Fig. 17 showing the application of the vertical back up strap for cooperation with the welding joint, said section being taken on the line 18—18 of Fig. 19, and Fig. 19 is a section taken on the line 19—19 of Fig. 18.

Referring to the drawings wherein like ordinals 25 designate like parts, it can be observed that the tank shell is denoted by reference character A and is of upright cylindrical or curved form having comparatively thin metal side panels B, floor sections C and roof sections D, which are assembled, 30 set up and welded together in a substantial manner so as to hold fluid and solid materials and withstand the pressure thereof without leaking.

Preferably the welded panels and sections of the shell are prefabricated and constructed of suitable uninterrupted or sectional length vertically 35 so as to provide continuous vertical seams or joints 10 at predetermined circumferential intervals apart, said seams extending from the floor to the ceiling of the tank. These panels or sections are adapted to be assembled and welded together for use in the field or at the location at which the tank is to be used. Also the panels or sections are adapted to be dismantled and reconstructed in tank form at a new location through 40 the use of improved means provided for the setting up and dismantling operation as will be hereinafter described. It is here noted that the side panels or sections B of the shell as shown in Figs. 2, 3 and 5 are arranged in their successive courses 45 not in break joint pattern as is customary but with perpendicular field seams 10 from bottom to top. Also the panels or sections B are respectively of reduced thickness successively upwardly so as to economize the amount and cost of necessary material for holding the contents of the tank. 50

In Fig. 6 the side panels are shown of uninterrupted length and uniform thickness upwardly, and in Fig. 7 the side panels are shown of uninterrupted length but of gradually tapering thickness upwardly so as to economize the amount of material which is necessary to effectively compensate lateral pressure exerted by the contents of the tank.

With one exception no uniqueness occurs in design or construction procedure in the matter of the bottom or roof sheet or plate (sometimes called deck), the exception being, as hereinafter particularly described, that in dismantling, segments of the bottom or floor are cut in a series of chord lines circumferentially (Fig. 8), each interchangeable segment being left welded to its contiguous shell section thus maintaining curvature of the latter and facilitating and expediting re-erection or construction of the tank.

The bottom or floor C as shown of the tank is of circular shape to the outer peripheral edge portion of which the lowermost end portions of the side panels or sections are tightly secured by welding at 11 (Figs. 6 and 11). The bottom being completed on a proper support or surface, a circle is inscribed corresponding with the inside diameter of the side wall of the shell and clip angles 12 (Fig. 3) are welded down with vertical leg portions thereof coinciding with the inscribed circle, facing outwardly as shown in Fig. 5. The spacing circumferentially of these clip angles 12 is such that one is centered at the bottom of each vertical seam between the side panels or sections, and one or more about evenly spaced along the arc of each panel (Figs. 2 and 3).

In erecting or dismantling the tank structure a pair of vertically disposed parallel channel runners E—E, nearly equal in length to the height of the side wall shell of the tank is secured to the contiguous side edge portions on the inner surfaces of adjacent side panels or sections on either side of the vertical seam or joint 10. Figs. 3, 5 and 13 show portions of two shell sections assembled firmly in and is typical of this erecting or dismantling feature. To the shell side sections are field tack welded the supporting brackets 15, their long dimensions being disposed horizontally and about radial. The channel runners E—E are secured to the brackets 15 by bolts 16, back to back with a space between for supporting, guiding and applying a cutting torch such as F, indicated in Fig. 13, but not connecting so as to provide a vertical passage between the runners back of the seam 10 for the free application of the tip of the cutting torch. Adjusting bolts such as 17 through the webs of the channel runners serve to hold the vertical abutting edges of the side panels or sections in close formation during the cutting operation of the torch when the tank is dismantled. In a somewhat similar manner the abutting edges of the members of the seam 10 are held in juxtaposed position by the runners during the setting up operation so that said seams can be externally welded. This method of supporting the side panels or sections of the shell is equally applicable when applied to the types shown in Figs. 3, 5, 6 and 7. Any number of the brackets 15 may be used to securely hold the side members of the shell with their adjacent side edges suitably juxtaposed for the welding application. Spacing tubes such as 18 (Fig. 3) may be used on the adjusting bolts 16 to define the adjustment of the members which form the seams 10 in each instance.

The space between the runners is preferably sufficient for a double tipped angle cutting torch

so that in dismantling, a V for the weld in the ensuing erection may be formed incident to the shell being cut through. The cutting torch of any sort (a single tipped one is indicated in Fig. 13), may have a simple glider 19 attached to it so that the runners serve as guides to provide a straight cut from top to bottom or vice-versa. In welding during the setting up operation it is not contemplated to use any glider.

After the bolts 17 are adjusted to give the device the desired or required gap for the vertical welds, the top angle band 20 may be next welded, after completing the inside seam weld, if any, down from the top a distance at least equal to the vertical leg of the angle band 20. The adjusting bolts 17 and their spacers 18 may also be used to support a staging bracket as hereinafter described. As the vertical seams are welded the bolts 17 are removed one at a time as interference with the torch occurs and may be replaced when inside weld in the vicinity of each is completed. The bottom to the shell fillets inside and outside should be completed in the proper order of procedure except in the case of the former at and in immediate vicinity of the vertical runners after these have been removed from their vertical temporary positions, the gaps so left should be welded.

Sometimes as alternate to clip angles 12 a base may be employed. In this construction the lower ends of the runners are clipped at 22 (Fig. 11) to accommodate member 21.

For the condition of single vertical field weld between panels or sections it may be an advantage to include a vertical back-strap 23 of the same or other metal or alloy on the sheet as shown in Figs. 16 to 19 inclusive. This may be tack welded, and if required or desired continuous welded after the vertical runners are removed. On the other hand it may be required or desired to remove the strap in which case it should be of different material than the shell, such as copper or aluminum in the case of a steel shell. Thus the strap 23 shown in Figs. 18 and 19 is temporarily secured by wood or metal wedges 25 behind the bolts 17 since for this condition there would be no need of moving brackets when outside welding is proceeding, there would be no interference with the bracket or parts thereof.

The staging bracket shown in Figs. 14 and 15 is detachably supported by the adjusting bolts 17 and channels E—E on the inside wall of the shell. These staging brackets serve to conveniently support a man during welding, cutting or setting up operation. Planks such as 26 constituting staging are supported by the horizontal support 27 and the hanger 28, said support and hanger being hooked over the bolts 17 and the hanger having a longitudinal turn buckle adjusting element 29.

Compliance with usual codes relative to roof structures usually necessitate a sufficient number of rafters to provide a pair of runners at every vertical seam without the wall panels or sections being too wide for trucks or railway transporting equipment, unless in exceptional cases the diameter is small compared with the height. This will sometimes occur in silo construction which may then require a few shapes of some sort for erection purposes only, but will not detract from the chief features of my improvement.

In the usual construction of the roof, a vertical central supporting column 30 is employed by

which the inner ends of the radiating rafters 31 are suitably supported, their outer ends being supported above the clip angles 32 and even with the upper edge of the side wall of the shell. The roof panels or sections D of suitable shape are welded together and to the top angle band 20 so as to assist in providing a light weight enclosure. The members constituting the radiating rafters of the roof may be used as the vertical runners which are employed for setting up or dismantling the side shell portions or wall of the tank.

In very large tanks the rafters will in certain instances require support between the side wall of the shell and center by one or more columns. For this purpose supporting girders 35 are typically shown in Fig. 10, supported by the auxiliary columns 36. In this case each rafter as erected may or will consist of a plurality of channels either lapped and bolted or joined longitudinally by a splice plate or plates such as 37.

In the case of the shell being very much higher than the length of a single channel a plurality of channel sections may be spliced and bolted together as shown in Fig. 12 by the splice members 38. As an alternate method of construction and erecting high tanks for use where the diameter is relatively small and particularly where the location is isolated there might be insufficient rafter channels for use as temporary vertical runners for the entire height. To overcome this condition I provide an intermediate angle ring 39 which in the illustration shown in Fig. 12 serves as backing for a horizontal welded joint in offset or staggered relation to the vertical seams. In the latter event a clip angle can be used. In either case the angle member is shown in section at 39 (Fig. 12), and on it are erected the channel runners such as E—E and procedure thereafter is as hereinbefore described for Figs. 3-5 etc.

Among advantages attained by my improved tank structure and method of facilitating the erection and dismantling thereof are the following:

1. Field welding and erection or dismantling equipment are minimized.

2. The erection of tanks is expedited, facilitated and simplified.

3. Labor and time employed for erecting or dismantling is reduced to a minimum.

4. By providing runners in conjunction with the vertical seams which function as guides for a cutting torch effectively assist in quickly and accurately cutting the side wall of the tank shell into sections, the numbers of which can be easily and quickly reassembled and reconstructed into a serviceable tank.

5. By providing simple and effective staging in conjunction with the erecting and dismantling operations the erection and dismantling of the tank structure is simplified, whereby time, labor and expense consumed are materially reduced.

6. Uniqueness is produced in that the shell side wall panels or sections are arranged on their successive courses not in break joint patterns but with perpendicular field welded seams from top to bottom, whereby time labor and expense are reduced, the construction is simplified, strength

of construction is increased and the assembly and dismantling operation are facilitated and simplified.

7. By providing panels or sections of tapering thickness continuously from the bottom to the top of the tank, said tapering being in corresponding proportion to the pressure of fluid or material held in the tank, strength of construction is consequently increased and the amount of material necessarily used is greatly reduced.

It is understood that the appended claim is to be accorded a range of equivalents commensurate in scope with the advance made over the prior art.

15 I claim:

In a tank structure, a base, an upright secured to the center of the base, a plurality of longitudinally curved panel units mounted on the base on end and extending one above the other with their vertical meeting edges in alignment with the meeting edges of adjacent upper and lower panel units, lugs secured to the vertical edges of the panel units and extending inwardly in spaced relation from one another and from the vertical edges of said panel units, structural bars connecting corresponding lugs of each superposed panel unit, said structural bars being arranged vertically in pairs arranged one on each side of

20 the vertical seam of the superposed panel units, threaded fasteners connecting each pair of structural members and arranged in spaced apart relation throughout the length thereof, spacing members mounted on certain of said threaded fasteners to hold said structural members and the vertical edges of the panel units in predetermined spaced apart relation, structural members connecting the uppermost course of panel units with their inner ends supported on the central upright and a sectional roofing structure supported by said last-named structural members, said vertical structural members being arranged internally of the tank structure and in spaced apart pairs to provide a guide to accommodate a welding torch while the vertical seam

35 40 45 is being welded.

JOSEPH T. SPARLING.
